(57) **CLAIM**

The ornamental design for a headset, as shown and described.

DESCRIPTION

FIG. 1 is a front perspective view of a headset showing our new design;

FIG. 2 is an outer side view thereof;

FIG. 3 is an inner side view thereof;

FIG. 4 is a bottom view thereof;

FIG. 5 is a top view thereof;

FIG. 6 is a front view thereof;

FIG. 7 is a rear view thereof;

FIG. 8 is a front perspective view of the headset in FIGS. 1-7 shown without broken lines or shading;

FIG. 9 is an outer side view thereof;

FIG. 10 is an inner side view thereof;

FIG. 11 is a bottom view thereof;

FIG. 12 is a top view thereof;

FIG. 13 is a front view thereof; and,

FIG. 14 is a rear view thereof.

The broken line showings of the earpiece, ear clip, circular region on the inner side, and the connector region in FIGS. 1-7 are for environmental purposes only and form no part of the claimed design.
